UNITED STATES PATENT OFFICE.

OTTO HUGO SHULTZ, OF WINDSOR, ONTARIO, CANADA, ASSIGNOR OF ONE-FOURTH TO LEONARD R. BENSON, OF WINDSOR, ONTARIO, CANADA.

DESIGN FOR AN APPAREL-HOOK.

49,317.

Specification for Design.

Patented July 4, 1916.

Application filed April 7, 1916. Serial No. 89,719. Term of patent 3½ years.

To all whom it may concern:

Be it known that I, Otto H. Shultz, a subject of the King of Great Britain, residing at Windsor, in the Province of Ontario and Dominion of Canada, have invented a new, original, and ornamental Design for Apparel-Hooks, of which the following is a specification, reference being had to the accompanying drawing, forming a part thereof.

I claim:

The ornamental design for an apparel hook, as shown.

OTTO HUGO SHULTZ.
